(57) **CLAIM**

The ornamental design for an electrical connector, as shown and described.

DESCRIPTION

FIG. 1 is a perspective view of the front, right side and bottom of an electrical connector showing our new design; FIG. 2 is a perspective view of the rear, left side and top thereof;

FIG. 3 is a front elevational view thereof;

FIG. 4 is a rear elevational view thereof;

FIG. 5 is a right side elevational view thereof;

FIG. 6 is a top plan view thereof;

FIG. 7 is a bottom view thereof;

FIG. 8 is a cross sectional view thereof, taken along line 8—8 as shown in FIG. 3; and,

FIG. 9 is a cross sectional view thereof, taken along line 9—9 as shown in FIG. 3.

The broken line showing of the environment is for illustrative purposes only and forms no part of the claimed design.
